COMBINED HANDLE AND BRUSH WIPER
FOR PAINT CANS

James D. Brennan, Bridgeport, Conn.

Application October 16, 1948, Serial No. 54,891

3 Claims. (Cl. 220—90)

1

This invention relates to new and useful improvements in hand tools and has particular relation to a tool comprising a wire can holder, lid lifter and brush wiper.

An object of the invention is to provide a tool of the kind indicated and formed of a single piece of wire and which is simple and inexpensive to make and which is useful for prying off the lids of cans, as a handle or holder for cans, and as a brush wiper for paint cans and the like.

Another object is to provide a tool as indicated and which is easily applied to and removed from a can and which is applicable to cans of slightly different sizes.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a top plan view of a tool made in accordance with the invention;

Fig. 2 is a side elevational view thereof;

Fig. 3 is an end view thereof, the view being taken as looking from the right in Fig. 1;

Fig. 4 is a top plan view showing the tool as applied to a can to form a holder or handle for the can and a brush wiper; and

Fig. 5 is a side elevational view showing the tool in such use, the view being taken as looking from the lower side of Fig. 4.

Referring in detail to the drawing, the improved tool generally designated 10 is shown as formed from a single length of relatively stiff wire bent upon itself intermediate its ends to provide a handle generally designated 11 and which is substantially U-shaped including a bight portion 12 and a pair of parallel or substantially parallel arms 13 and 14 located substantially in the same plane. At its forward end, arm 13 is curved downwardly and rearwardly providing a bight portion 15 which is generally at right angles to the plane in which the arms 13 and 14 are located.

Thereafter, the wire of the arm 13 is carried rearwardly as at 16 and is again bent at 17 to provide a transversely extending portion 18 arranged below the plane of the arms of the handle 11 and at right angles to said arms and, in fact, extending from a position beginning below the

2

forward portion of the arm 13 to a position laterally outwardly of the arm 14. The free end of the extension 18 is flattened as at 19 providing a lid lifter. It is noted that the flat 19 is in a plane normal to the plane of the handle 11.

When the tool is used as a lid lifter the flat 19 is forced under the flange of a can lid and at such time the general position of the tool will be such that its longitudinal axis is approximately parallel with the longitudinal axis of the can. Then on a partial rotation of the tool, or an attempt to rotate the tool with the flat 19 as a fulcrum point, the lid (of the friction type) is pried from a can.

15 The arm 14 of handle 11 projects forwardly substantially beyond the bight 15 above described to complete the can holder and to provide a brush wiper when the tool is in position on a can. As probably best shown in Figs. 1 and 4, 20 the wire constituting the arm 14 of the handle is bent slightly at 20 and then extends forwardly and laterally and downwardly at 21. Here it is noted that this portion 21 comprises a brush wiper when the tool is attached to a can. The 25 extreme forward end of the arm 14 is preferably slightly curved providing a curved free end portion 22 which is relatively stiff and yet has a certain resilience.

It is planned that the tool 11 be of very simple 30 and inexpensive construction whereby it may be sold at a very low price or even given to a customer purchasing a can of paint or the like. For the purpose of identification, or where the device is used as an advertising medium, a portion of 35 one arm of the handle may carry some identifying data. Thus, in the drawing, a mid portion of the arm 13 of handle 11 is flattened as at 23 and such flattened portion may carry a name or trade-mark or the like. Obviously, such identifying material may be applied to the tool in 40 other recognized ways.

The present tool is particularly designed for 45 use by a householder when working with a small can of paint. Paint in small quantities, such as pints, quarts and even smaller quantities, is sold in cans not equipped with handles of any type. Such cans are of a rather standard construction and a portion of one such can is indicated at 24 in Figs. 4 and 5. The can there shown is of pint 50 size and includes a circular wall 25 at its upper end equipped with an internal flange 26 immediately about the edges of the wall and which flange is provided with the usual channel or groove 27 for the reception of a flange portion 55 of a friction type cover or lid (not shown) common in the art.

Above, the use of the lid lifter feature of the present invention was described but here it is again noted that when the flat 19 is forced under the flange of a friction lid or cover, the handle of the tool is then available as a lever for twisting or rotating the tool so as to pry up such lid or cover. The cover being removed, the tool is applied to the can as shown in Figs. 4 and 5.

In applying the tool, assuming the can to be disposed on a horizontal surface or otherwise supported with its open side upwardly, the householder inserts the long arm, comprising portions 21 and 22, of the tool into the container the tool being held at a relatively steep angle. Then the bight 15 of the tool is hooked over the inner edge of the flange 26 of the can. This also brings the arm 18 of the tool substantially under such flange and then the user or householder rocks downwardly on the handle. This brings the curved end portion 22 of the long arm of the tool against the inner surface of the opposite portion of the wall 25 of the can and at the end of the rocking movement such curved portion will be under a portion of the flange 26 generally at the opposite side of the can from that under which the arm 18 of the tool is located.

As the brush wiper portion 21 of the tool diverges laterally and downwardly from the inner end of the handle arm 14, the curved portion 22 will not be directly opposite the handle but will be laterally offset with respect to it. This keeps the brush wiper portion 21 laterally of the center of the can so as not to be in the way of a brush being dipped in and removed from the contents of the can. The curve 22, as above explained, is stiff yet somewhat resilient having been forced into the position described and contacting the inner surface of the can wall as at 28 causes the bight 15 to be forced against an inner edge of the flange 26. Portion 22 being resilient as described, it will be seen that it may yield more or less and thus accommodate the tool to cans of slightly different sizes.

In addition to the engagement at 28 and engagement of the bight 15 with an inner edge portion of flange 26, the curved portion 22 is tight against the underside of a portion of the flange at 29 (Fig. 5) and the inner portions of the handle arms 13 and 14 are against the outer edge of the flange 26 across the can from such described point of engagement 28. Thus, the tool is rigidly applied to the can and may be used as a handle or holder for carrying the can about. Additionally, when the householder dips his brush into the contents of the can he may wipe the excess paint, varnish or the like from the brush on the brush wiper 21 provided by the present tool.

Any such excess paint thus wiped falls back into the can and will have no tendency to, by gravity or capillary action, move out of the can. In fact, portion 21 being inclined downwardly, the gravitational tendency of the paint or the like wiped on such portion will be back into the can even though it flows along the portion 21 until it engages the flange 26. Thus, with the present tool, the householder has a convenient means for moving or handling or carrying the paint can from place to place and he also has a means which saves him from wiping the dipped brush against the flange 26. This latter practice usually results in channel 27 becoming filled or partly filled with paint, varnish or the like, the latter then spilling over onto the sides of the can.

Having thus set forth the nature of my invention, what I claim is:

1. In a tool of the character described, a single length of wire bent upon itself intermediate its ends to provide a U-shaped handle including a pair of spaced horizontally aligned arms and a horizontal bight portion, one of said arms at its forward end bent downwardly, then rearwardly providing a hook portion to extend about the rim of a can, said arm then again bent and extending laterally toward the other arm in a plane below the latter to engage spaced portions of the underside of a can rim over which said hook has been engaged, and the other of said arms continued forwardly beyond the forward end of the first mentioned arm to span the can and engage the underside of a rim portion of the can at the side of the can opposite that engaged by said hook, and the free end of said other arm curved to follow the inner contour of said other side of the can.

2. In a tool of the character described, a single length of wire bent upon itself intermediate its ends to provide a U-shaped handle including a pair of spaced horizontally aligned arms and a horizontal bight portion, one of said arms at its forward end bent downwardly, then rearwardly providing a hook portion to extend about the rim of a can, said arm then again bent and extending laterally toward the other arm in a plane below the latter to engage spaced portions of the underside of a can rim over which said hook has been engaged, the other of said arms continued forwardly beyond the forward end of the first mentioned arm to span said can and engage the underside of a rim portion of the can at the side of the can opposite that engaged by said hook, and said other arm also bent to extend laterally whereby not to extend across the center of the can.

3. In a tool of the character described, a single length of wire bent upon itself intermediate its ends to provide a U-shaped handle including a pair of spaced horizontally aligned arms and a horizontal bight portion, one of said arms at its forward end bent downwardly, then rearwardly providing a hook portion to extend about the rim of a can, said arm then again bent and extending laterally toward the other arm in a plane below the latter to engage spaced portions of the underside of a can rim over which said hook has been engaged, and the other of said arms continued forwardly beyond the forward end of the first mentioned arm to span the can and engage the underside of a rim portion of the can at the side of the can opposite that engaged by said hook.
